OTTO LAUBER, OF BREDENEY, AND FRIEDRICH STOCK, OF ESSEN-ON-THE-RUHR, GERMANY, ASSIGNORS TO FRIED. KRUPP AKTIENGESELLSCHAFT, OF ESSEN-ON-THE-RUHR, GERMANY.

SPADE-FASTENING FOR WHEELED GUN-CARRIAGES.

1,079,868.

Specification of Letters Patent.

Patented Nov. 25, 1913.

Application filed August 30, 1910. Serial No. 579,724.

To all whom it may concern:

Be it known that we, OTTO LAUBER, residing at Bredeney, Germany, and FRIEDRICH Stock, residing at Essen-on-the-Ruhr, Germany, both subjects of the Emperor of Germany, have invented a certain new and useful Improvement in Spade-Fastenings for Wheeled Gun-Carriages, of which the following is a specification.

10 This invention relates to spade-fastenings for wheeled gun-carriages, particularly for wheeled carriages of heavy ordnance, and particularly to such a spade-fastening that makes it possible to use a spade, intended for 15 soft ground, and wherein the spade has such large dimensions that when transporting the gun, the spade must be removed from the trail.

20 The object of this invention is to allow that the spade on the one hand may easily and quickly be attached to or removed from the trail and on the other hand need not be lifted out of the ground when the gun is trained.

25 In the accompanying drawing is shown one embodiment of the application by way of example.

30 In the different views shown:—Figure 1 illustrates the trail of a wheeled gun-carriage partly in side view, with the spade in longitudinal section. Fig. 2 is a plan view of Fig. 1 partly in section. Fig. 3 shows separately the trail as employed in Fig. 1. Fig. 4 discloses separately the spade shown 35 in Fig. 1. Fig. 5 is a detail in side-view. Fig. 6 is the left end view of said detail.

40 The trail consists of two E-shaped side walls A connected by means of a shoe B inclosing their ends, and a cross bar C disposed adjacent said shoe.

45 The spade D, D¹ consists principally of the spade-shaped blade D and the press-plate D¹. The spade-blade D and the press-plate D¹ are held together by strengthening 50 ribs d². On the press-plate D¹ is situated a narrow flange d³, the function of which is to engage with the horizontal rib or flange c¹ of the cross bar C. The press-plate D¹ is provided with a wide flange d⁴ against 55 which the rear face b⁴ of the shoe B is resting when the spade D, D¹ is connected with the trail. Besides the flanges d³, d⁴ and the cross bar C, there are also two clutches or

clamps E (see Figs. 5 and 6) serving as connections between the spade and the trail. 55 Each of these clamps may be set between a pair of lugs b¹, situated on the shoe B, and be secured to their respective pair of lugs by means of key-bolts F. The clamps E have hooks e¹ designed for engagement with 60 the flange d⁴ and a surface e² resting on the surface b² of the shoe B, when said clamps E are engaged with the flange d⁴ and are connected with the lugs b¹ by means of the 65 key-bolts F.

To make it possible to displace the carriage sidewise on the spade D, D¹ the shoe B is furnished with a tooth-rack b³ and the spade D, D¹ with a pinion G mounted in a bearing thereon and meshing with the tooth-rack. This pinion is mounted with its pivot 70 g¹ in the socket d⁵ on the spade's press-plate D¹. The pinion G has a head piece g² provided with openings g³ for a hand lever H.

The edge c¹ of the cross bar C, the rack b³, 75 the front face b⁴ of the shoe B and the flange d⁴ are all curved concentrically around one center situated equidistant from each wheel on a line connecting their resting points on the ground.

To attach the spade to the trail one may proceed in the following manner: When the spade has been buried in the ground, the trail is brought to rest on the press-plate D¹ of the spade in such a way that the horizontal leg of the cross bar C lies directly in front of the outermost edge of the flange d³. Then the trail is moved so far rearward on the press-plate D¹, that the rear face b⁴ of the shoe B rests against the flange d⁴. 80 By this means the cross bar C engages with the flange d³ and the tooth-rack b³ enters into mesh with the pinion G. Lastly the clamps E are inserted between the lugs b¹ and locked by the key-bolts F. The spade 85 is then so attached to the trail that it is unable to detach itself therefrom, and that the shocks from firing the gun are transferred to the spade. When it is desired to train the carriage the trail is shifted on the press-plate D¹ of the spade by turning the pinion G with the hand-lever H. Then the cross bar C will slide along the flange d³ and the shoe B along the flange d⁴. How the spade 90 D D¹ is removed from the trail needs, after 100 the foregoing, no explanation.

What is claimed is:—

1. The combination with a wheeled gun-carriage having a trail and a spade, of means for easily detaching or attaching said spade to the trail-end, constructed to permit a horizontal displacement between trail-end and spade, said spade being provided with fixed connecting members and a movable gearing member and said trail provided with fixed connecting members and a gearing member, said several members adapted to be brought into engagement with the respective spade members by a mutual displacement of the trail and the spade in the longitudinal direction of the gun-carriage.
2. The combination with a wheeled gun-carriage having a trail and a spade, of means for detachably mounting said spade on the trail-end, constructed to permit a lateral displacement between trail-end and spade, said means being brought into engagement by running the trail rearward on the spade, and clutches bolted to the trail and locking the spade to the trail-end.
3. The combination with a wheeled gun-carriage having a trail and a spade, of means for easily detaching said spade from, or attaching it to the trail-end, gearing comprising rack and pinion for producing lateral

displacement between trail-end and spade, 30 said spade and trail being each provided with two connecting members comprising transverse flanges on the spade and transverse opposing flanges on the trail-end brought into engagement with each other by running the trail rearward on the spade. 35

4. The combination with a wheeled gun-carriage having a trail and a spade, of means for detachably mounting said spade on the trail-end, said means comprising transverse 40 jaws or flanges on the spade and opposing transverse flanges on the trail-end, and clutches bolted to the trail; and the spade being provided with a pinion and the trail with a rack forming a gear for effecting lateral displacement of the trail on the spade; said gear being brought into mesh and said flanges being brought into engagement simultaneously by running the trail rearward on the spade, substantially as described. 45

The foregoing specification signed at Bar-
men, Germany, this 23rd day of July, 1910.
